REFINING MINERAL LUBRICATING OILS

James Morris Page, Jr., Casper, Wyo., assignor to
Standard Oil Company, Chicago, Ill., a corpora-
tion of Indiana

Application February 17, 1936, Serial No. 64,217

5 Claims. (Cl. 196—13)

This invention relates to a process of refining mineral oils and specifically petroleum lubricating oils of the type employed in the lubrication of internal combustion engines and commonly known as motor oils. The invention further relates to a process of extracting such oils with a specific solvent, namely, beta beta' dichlor diethyl ether, hereinafter referred to as "chlor-ether." The use of this solvent for the extraction of mineral lubricating oils has been previously described in United States Patent No. 2,003,238, entitled "Process of separating mineral oils" by H. T. Bennett, filed June 23, 1933.

More particularly, the present invention relates to an improvement in the use of beta beta' dichlor diethyl ether in lubricating oil extraction processes wherein undesirable naphthenic constituents are removed from the paraffinic component of the oil. One object of the invention is to facilitate the use of said chlor-ether solvent in the extraction of wax-containing lubricating oil stocks. Another object of the invention is to increase the selective solvent action of said solvent by the addition of minor amounts of certain modifying agents.

In the extraction of midcontinent and Salt Creek lubricating distillates such as motor oil distillates falling within the viscosity range of 20—60 S. A. E. number, difficulty has frequently been encountered with separation of wax in the extraction process. Where the distillate contains over 5% of paraffin wax and frequently as much as 10 or 15% thereof, the wax will usually crystallize in the form of a thick mush or magma at ordinary temperatures and even at temperatures in the range of 100—125° F. This is especially true of the heavier distillates which contain higher melting waxes.

When extracting such wax-containing oils with beta beta' dichlor diethyl ether it is usually necessary to maintain the temperature of the oil undergoing extraction below 110° F. in order to obtain a satisfactory yield of refined lubricating oil, or raffinate, having the desired viscosity index. It is, accordingly, not feasible to carry out the extraction process at a temperature sufficiently high to maintain the wax in liquid form.

I have now discovered that the extraction of mineral lubricating oils with chlor-ether is greatly improved by incorporating in the chlor-ether a small amount, usually from 2 to 20%, but possibly as much as 30%, of propylene glycol. I have found that propylene glycol is miscible with chlor-ether to a very considerable extent as shown by the following table which indicates the solubility

at various temperatures of propylene glycol in beta beta' dichlor diethyl ether, saturated with water (about 1%).

Temperature	Propylene glycol in mixture, percent	5
°F.		
91	1.96	10
100	5.65	
106	7.38	
110	9.08	
113	14.49	
115	16.67	
105	50.00	

The lowering of the miscibility temperature at concentrations of propylene glycol in excess of about 16% is due to the reduction in the proportion of water in the mixture.

I have also found that the miscibility temperature of mineral oil and chlor-ether is very materially raised by the addition of propylene glycol. The following table shows the effect on the miscibility temperature of chlor-ether and a cylinder stock derived from Salt Creek crude. Three ratios of solvent to oil are given, and temperatures of complete miscibility of oil and solvent are given with and without the addition of 13% by volume of propylene glycol to the chlor-ether.

Ratio of chlor-ether to oil	Miscibility temperature	Misc. temp. with 13% propylene glycol		35
		Degrees	Degrees	
1:1	148	226		
2:1	155	206		
3:1	165	198		

By using propylene glycol to modify the solvent action of chlor-ether in this manner I am enabled to carry out my refining operation at temperatures ranging from 120 to 200° F. The propylene glycol prevents the chlor-ether from dissolving, at these relatively high temperatures, excessive amounts of those hydrocarbons which are desired in the raffinate, yet it does not prevent the solution of naphthenic constituents of the oil in the solvent.

As an example of the use of my new modified chlor-ether solvent, two volumes of pure chlor-ether to one volume of Salt Creek cylinder stock were used in an extraction carried out at 140° F. A yield of raffinate oil of 58.2% was obtained, the oil having a viscosity index of 88. In comparison

with this two volumes of chlor-ether solvent containing 13%, by volume, of propylene glycol was applied to one volume of the same oil at the same temperature and a yield of 80% of raffinate oil was obtained, the oil having a viscosity index of 85.2, only slightly lower than the viscosity index obtained without the use of propylene glycol. It is characteristic of my process that, when conditions are selected such that the yield 10 of raffinate oil obtained is greatly increased, the viscosity index is adversely affected only a very little, if at all. Not only is the yield increased but the selectivity of the solvent at relatively high extraction temperatures is also improved 15 and a sharper separation is obtained between the undesired naphthenic constituents of the oil and the desirable paraffinic hydrocarbons.

The effect of the addition of propylene glycol to chlor-ether may also be observed by referring 20 to the accompanying drawing which forms a part of this specification. The graph shows the results of extracting a mineral lubricating oil distillate of 60 S. A. E. viscosity range derived from Salt Creek crude. It will be noted from the chart 25 that for a given yield of raffinate oil, the permissible temperature of operation is greatly increased by the addition of propylene glycol. Thus, at a 75% yield, chlor-ether requires a temperature of 112° F. whereas chlor-ether with 8% 30 propylene glycol requires a temperature of about 138° F., well above the melting point of this waxy oil. Likewise, 12% propylene glycol permits a temperature of 158° F. with this same yield.

One of the advantages of my process results 35 from the fact that the solubility of propylene glycol in beta beta' dichlor diethyl ether is very small at low temperatures and therefore I may separate the propylene glycol from the chlor-ether by cooling to 34° F. or lower, for example, 40 to 20° F. When water is present in the chlor-ether solvent, it is not necessary to cool as low as this, and with chlor-ether saturated with water, separation of propylene glycol (and water) occurs at about 80° F. In this case, cooling below 45 80° F., for example to 50° F., will result in separation of the glycol.

On cooling two layers are formed, the upper layer consisting of substantially pure propylene glycol. In carrying out my process I prefer to 50 analyze the solvent before use to determine the amount of propylene glycol modifying agent which is present and then adjust the concentration by adding to the solvent supply the necessary amount of either chlor-ether or propylene 55 glycol.

I may also initially extract a wax-containing oil at an elevated temperature above the melting point of the wax using between 10% and 30% of propylene glycol in the solvent mixture. I 60 may then cool the extract phase to a comparatively low temperature of the order of 50° F. to 90° F. whereupon propylene glycol and a further quantity of oil or raffinate is caused to separate. This second raffinate fraction may then be further treated in the process or it may be disposed of as a second grade lubricating oil having intermediate viscosity index.

Having thus described my invention, what I claim is:

70 1. The process of extracting undesirable constituents from wax-containing mineral lubricating oils which comprises intimately contacting the oil with a solvent comprising beta beta' dichlor diethyl ether and from 2-30% of propylene 75 glycol, maintaining the temperature of the con-

tacting operation above the solidifying point of said wax-containing lubricating oil, separating said solvent and undesirable oil constituents from the refined mineral lubricating oil and thereafter recovering said solvent from said refined mineral oil and said undesirable oil constituents. 5

2. In the process of extracting undesirable naphthenic constituents from wax-containing mineral lubricating oils with beta beta' dichlor diethyl ether, the improvement comprising incorporating in said ether 2-20% of propylene glycol and maintaining the temperature of said extraction operation above the miscibility temperature of said ether and said mineral oil but below the miscibility temperature of said mineral oil 15 and said ether containing said propylene glycol. 10

3. In the process of extracting undesirable naphthenic constituents from mineral lubricating oils wherein the oil is intimately contacted with beta beta' dichlor diethyl ether and the undesirable constituents are removed as an extract in solution in said ether, the improvement comprising adding to said ether from 5 to 30% of propylene glycol, conducting the extraction at a temperature above the solidifying point of the 25 oil, separating the oil-solvent mixture into a raffinate fraction and an extract fraction, cooling said extract fraction to a temperature below 80° F. whereby said propylene glycol is caused to separate from said extract fraction and separating and recovering said propylene glycol for use in further extraction of additional quantities of mineral lubricating oil. 30

4. In the process of extracting undesirable naphthenic constituents from mineral lubricating oils wherein the oil is intimately contacted with a solvent comprising beta beta' dichlor diethyl ether, the oil and solvent mixture are permitted to separate into a raffinate fraction and an extract fraction, the raffinate fraction is subjected to distillation to recover said solvent for reuse and produce a refined lubricating oil, and the extract fraction is subjected to distillation to recover the solvent for reuse and produce an extract oil which is rejected, the improvement comprising modifying the solvent action of said beta beta' dichlor diethyl ether by adding thereto a proportion of propylene glycol within the range of 5 to 30%, recovering said propylene glycol from said chlor-ether solvent obtained on distillation of said extract fraction by cooling said recovered solvent below 85° F. and re-employing said recovered propylene glycol in the extraction process in the desired proportion to said chlor-ether. 40 45 50 55

5. In the process of extracting lubricating oils containing paraffin wax with beta beta' dichlor diethyl ether wherein the oil is intimately contacted with the ether and the oil and ether are separated in two phases in which the heavier ether phase contains dissolved undesirable naphthenic constituents of the oil, the improvement comprising avoiding difficulties resulting from the separation of solid paraffin wax as a third phase in the process by adding between 5% and 20% of propylene glycol to the beta beta' dichlor diethyl ether whereby the miscibility temperature of said ether and said lubricating oil is raised substantially above the melting point of said waxy oil, and conducting the extraction at a 70 temperature between the melting point of said waxy oil and the said miscibility temperature, whereby said wax is prevented from crystallizing as a separate phase from said mixture. 65 70 75
